UNITED STATES PATENT OFFICE

2,607,203

REFRIGERATION PLATE WITH DEFROSTING MEANS

Herman W. Kleist, Chicago, Ill., assignor to Dole Refrigerating Company, Chicago, Ill., a corporation of Illinois

Application December 22, 1947, Serial No. 793,201

4 Claims. (Cl. 62—115)

1

My invention relates to an improvement in defrosting devices, and has for one purpose to provide means for defrosting a refrigerating coil.

Another purpose is to provide means for defrosting a refrigerating plate in which a volatile refrigerant is normally evaporated within the plate, in a coil housed within the plate.

Another purpose is to provide an improved refrigerating plate in which both a refrigerating and a defrosting coil are included.

Other purposes will appear from time to time in the course of the specification and claims.

I illustrate the invention more or less diagrammatically in the accompanying drawings wherein:

Figure 1 is a side elevation illustrating a group or battery of my plates embodying the present invention;

Figure 2 is an end elevation of the structure of Figure 1;

Figure 3 is a bottom plan view with parts in section; and

Figure 4 is a section on an enlarged scale on the line 4—4 of Figure 1.

Like parts are indicated by like symbols throughout the specification and drawings.

Referring to the drawings, I illustrate a plurality of plates generally indicated as 1, each of which may conveniently be formed by sheet metal members 2, 3, having connecting side flanges 4. Positioned within each plate is an evaporating coil, generally indicated as 5, each such coil having an inlet pipe 6 and an outlet pipe 7. The coil 5 is housed in the space within and between the sheet members 2 and 3.

While I do not wish to limit myself to vacuum plates, I find it convenient to provide means for partially evacuating the interior of the plates. I illustrate, for example, a fitting 8, through which the air may be partially evacuated, and the fitting then closed. Since the fitting does not, of itself, form part of the present invention, it is not herein shown in detail. It will be understood, however, that the reduction of the pressure within the plate to less than atmospheric is effective to force the sheets 2, 3 against the coil 5 in satisfactory heat conductive relationship.

As a matter of convenience, I illustrate the plate as having outwardly extending edge portions 9 which may be received in notches 10 of any suitable structural supports 11. It will be understood that the details of the plates and of the supporting means may be widely varied. Referring, for example, to Figure 3, I illustrate a heating or defrosting coil or pipe 15, which may

for example, receive hot water or any other suitable fluid or liquid raised to a temperature sufficient to defrost the plate. I illustrate, for example, a hot water inlet 16 connected to the pipe or coil 15 by a water delivery pipe 11. I illustrate the pipe or coil 15 as passing around three edges of the plate and ending in a discharge pipe 18 extending to a suitable outlet 19.

In the embodiment of my invention herein shown, I illustrate a plurality of plates 1 arranged in parallel relationship and gripped, for example, between structural members 11, with their notches 10, the structural members being connected by rods or long bolts 20 with their heads 21 and nuts 22. Where the unit is used in air conditioning, or in cooling air in connection with locker plants and the like, the individual plates 1 may be closely spaced, and may be separated by relatively small intervening spaces 23, which may advantageously be of substantially uniform clearance.

Any suitable means may be used for cycling a volatile refrigerant through the coils 5 of the individual plates. I illustrate a discharge manifold 26, the plates being arranged in parallel. Any suitable means for cycling a volatile refrigerant may be employed, the details of which do not form part of the present invention, and are therefore not shown. I may provide a similar arrangement for circulating the defrosting medium, such as hot water. I illustrate, for example, an inlet manifold 16 and an outlet manifold 19, which constitute, respectively, the inlet and the outlet for the individual pipes or connections 17 and 18.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

I illustrate herein a type of plate which may advantageously be used for a forced air railway car refrigerating unit, in which air from the interior of the frozen storage space of a refrigerator car is passed between long and closely spaced plates, and is thereafter returned to the interior of the car. It will be understood that when so used, the group of plates may be suitably housed or jacketed, to define a passage for

the air. However, in the present invention, the primary purpose is to provide a hot water or hot fluid defrosting arrangement for the plates, whether the plates are used in railway refrigeration, domestic refrigeration, commercial refrigeration, or the like.

It will be understood that each individual plate contains one of the evaporating coils 5. I illustrate each plate as having, in its interior, but adjacent its edges, one of the defrosting ducts or pipes 15. Such an arrangement is adequate where a narrow plate is used. It will be understood, however, that if a plate substantially wider than those herein shown is used, a larger number of bends of hot water or defrosting tubing may be employed. In either event, the hot water tubing is incorporated in the plate, and is of a substantially shorter length than the length of tubing or piping used for the evaporation of the volatile refrigerant. There is thus a minimum interference with the freezing efficiency of the plate as a whole.

An important factor in the use of plates made in accordance with my invention is that the hot fluid passage 15 is in heat conductive association with the plane walls 2, 3 of the plate. Thus heat is rapidly propagated, across the walls of the plate, there being a sufficient temperature rise to free the frost from the surface. In many instances, it is not necessary to melt off the frost. It may be merely loosened, so that it may more easily be scraped off. It is of maximum importance, initially, to break the bond at the edges of the plate. Then the shell or layer of frost becomes so loosened as to be readily removed. If the plate is in vertical position, it may drop off by itself, or be very readily scraped or tapped off. Hence, a marginal passage, around the edge of the plate, is, in general, more important and more helpful than an intermediate passage; although one or more intermediate passages may be necessary in the case of plates of substantial or excess breadth.

I claim:

1. In a refrigerating plate, and means for defrosting it, a gas-tight housing including outer walls, an evaporator coil positioned within said walls and in heat-conductive relationship with said walls, said coil having an inlet and an outlet separate from said inlet extending through said walls, and a defrosting coil adapted for circulating a defrosting fluid through said plate, said coil being positioned within the interior of said

plate and having the same heat-conductive relationship with the same walls as that of the evaporator coil and having an inlet and an outlet separate from said inlet extending through the walls of said plate, and a fitting in the housing through which air may be exhausted from the interior of the housing, whereby the walls are held in heat conductive relationship by the external atmospheric pressure, with both the evaporator coil and the defrosting coil in heat conductive relationship with said walls.

2. In a cold plate adaptable for use in refrigerating structures, a gas-tight housing including two parallel, plane, outer walls sealed together about their edges to enclose a gas-tight interior, an evaporator coil positioned within and between said walls and in heat-conductive relationship with said walls, said coil having an inlet and an outlet, and a defrosting coil adapted for circulating a defrosting fluid through the interior of said plate, said defrosting coil being positioned within the interior of said plate and in heat-conductive relationship with said walls, and having an inlet and an outlet independent of the inlet and outlet of the evaporator coil, said evaporator coil and said defrosting coil being of the same gauge and having a like conductive relation to the same walls of the plate.

3. The structure of claim 2 characterized in that the defrosting coil extends about the evaporator coil.

4. The structure of claim 2 characterized in that the defrosting coil extends about the evaporator coil and is located adjacent but within the outer edge of the space within the gas-tight housing.

HERMAN W. KLEIST.
